UNITED STATES PATENT OFFICE.

WILLIAM M. KELLOGG, OF PITTSFIELD, MASSACHUSETTS, ASSIGNOR TO
THE YANKEE NOVELTY COMPANY, A CORPORATION OF MAINE.

SCISSORS-SHARPENER.

No. 841,537.

Specification of Letters Patent.

Patented Jan. 15, 1907.

Application filed July 6, 1905. Renewed June 20, 1906. Serial No. 322,609.

To all whom it may concern:

Be it known that I, WILLIAM M. KELLOGG, a citizen of the United States, residing at Pittsfield, in the county of Berkshire and State of Massachusetts, have invented certain new and useful Improvements in Scissors-Sharpeners, of which the following is a specification.

This invention relates to an improved sharpener for scissors or similar articles, and has for its primary object to produce a device of this character by the use of which a pair of scissors can be very quickly and easily sharpened, which is very light in weight and compact in structure, and which can be manufactured and sold at a very small cost.

With these objects in view it consists, essentially, of a wooden base, the upper face of which is provided at one end with a recess adapted to receive an abrading-block and a guide member adjustably secured to the base, so that the entire surface of the abrading-block can be utilized by sliding the guide member back and forth.

For a full description of the invention and the merits thereof and also to acquire a knowledge of the details of construction of the means for effecting the result reference is to be had to the following description and accompanying drawings, in which—

Figure 1 is a perspective view showing the application of my device. Fig. 2 is a longitudinal sectional view. Fig. 3 is a detail perspective view of the parts.

Corresponding and like parts are referred to in the following description and indicated in all the views of the drawings by the same reference characters.

The numeral 1 designates the base which is preferably formed out of a rectangular piece of wood and is provided at one end with a transverse groove or recess 2. It must be understood, however, that the base can be made in any suitable shape or size without departing in any manner from the spirit of the invention. An abrading-block 3 is located in the recess 2 and is preferably in the form of a file, the serrations of which run at an angle to the edges of the block. The thickness of the file 3 is somewhat less than

the depth of the recess 2, so that its outer face lies in a plane below that of the top of the base 1. The file 3 is roughened upon both faces and is secured in position by means of a tack 4 or other suitable fastening, so that it can be readily reversed when one face becomes worn. A guide member 5 is secured to the base by means of a screw 6, operating in a slot 7. One end of this guide member 5 is beveled at 6 and projects over the file 3, so as to form a suitable guide for the blade of the scissors.

When the scissors-blade is moved against the inclined plane 6 of the guide member 5, the edge of the blade is drawn across the file at such an angle as to cause it to take the proper bevel. By adjusting the guide member 5 longitudinally upon the base 1 the entire surface of the file can be utilized, and hence the device will prove very economical in operation. Owing to the fact that the depth of the recess 3 is greater than the thickness of the file, the projecting end of the guide member 5 will be spaced from the top of the file. This accomplishes the very important result of preventing the accumulation of filings during the sharpening process and also adds very materially to the efficiency of the device. When one face of the file becomes worn, the operator can remove the tack 4 and by reversing the file obtain practically a new sharpener.

It will thus be understood that I have invented a very simple device for the purposes specified, which will be very economical in operation and which will prevent the customary accumulation of filings, which detracts from the efficiency of the device.

Having thus described the invention, what is claimed as new is—

In a scissors-sharpener, the combination of a base-block having a recess extending transversely thereacross, an abrading-block removably secured within the recess, the outer face of said abrading-block lying in a plane somewhat below that of the face of the base-block, means for holding the abrading-block in position, a guide member having a beveled end which projects over and is spaced from the abrading-block and also having a slot running in a direction at approximately

right angles to the beveled edge, and a clamping member passing through the slot and having connection with the base-block, the space between the guide member and the 5 abrading-block serving as a trap to catch the filings and prevent them from interfering with the effective operation of the device.

In testimony whereof I affix my signature in presence of two witnesses.

WILLIAM M. KELLOGG. [L. s.]
